UNITED STATES PATENT OFFICE.

CHARLES H. HODGKINS, OF PITTSBURGH, PENNSYLVANIA, ASSIGNOR TO WESTINGHOUSE ELECTRIC & MANUFACTURING COMPANY, A CORPORATION OF PENNSYLVANIA.

PROTECTIVE DEVICE.

Application filed November 8, 1924. Serial No. 748,606.

My invention relates to thermal protective devices and particularly to thermal relays.

The object of my invention is to provide a relatively simple, compact, and easily manufactured thermal relay that shall operate with a snap action.

In practicing my invention, I provide a current-conducting, thermally-responsive element of relatively small heat-storage capacity, and a second current-conducting thermally-responsive element of greater heat-storage capacity than the first element and having a portion that serves as a latch for the first element.

15 In the single sheet of drawings,

Figure 1 is a diagrammatic view of an electric circuit comprising the device embodying my invention,

Fig. 2 is a diagrammatic view of the circuit illustrated in Fig. 1, with the circuit-controlling means in its open position;

Fig. 3 is a top plan view of one thermally-responsive element of the device embodying my invention,

Fig. 4 is a view, partially in side elevation and partially in section, of the parts illustrated in Fig. 3,

Fig. 5 is a top plan view of a second, thermally-responsive member.

Fig. 6 is a view, mainly in side elevation but partially in section, of the device shown in Fig. 5,

Fig. 7 is a view, mainly in side elevation, of a device embodying my invention, a portion thereof being shown in section, and

Fig. 8 is an assembled view, in perspective, of a device embodying my invention.

Referring more particularly to Figs. 3 to 8, inclusive, a thermal relay 11 comprises a thermally-responsive element 12 that is substantially straight and comprises two suitable metal plates, having dissimilar expansion characteristics, closely united to form a bimetallic strip. The member 12 is provided with a plurality of longitudinal parallel slots or cuts 13 and 14, respectively, extending inwardly from its opposite ends in order to provide a relatively long path for electric current traversing the member, whereby the same is heated and one end thereof is caused to be moved, in a manner well known in the art.

One end of the member 12 is mounted on

a laterally disposed supporting bar 15, of electric insulating material, and a second bar 16, of electric insulating material, is located upon the opposite surface of the member 12 and is adapted to be clamped thereagainst in order to hold the member 12 securely against the supporting member 15.

A member 17, of substantially U-shape, and of electric insulating material, is mounted upon the free end of the member 12, and held in proper operative position by a plurality of small bolts or rivets 18 which extend into a metal bar or plate 19 located on one side of the member 17, to constitute a wearing plate, for a purpose to be herein-after set forth in detail.

One end of a second bimetallic element 21 is fastened to the other surface of the supporting bar 15 and comprises a plate that is substantially co-extensive with the element 12 but has, in addition thereto, a return-bent portion 22 that extends around the free end 75 of the element 12, substantially as illustrated in Figs. 7 and 8 of the drawings.

A plurality of pairs of opposite and longitudinally extending slots 23 and 24 are provided in the member 21, as is more particularly illustrated in Fig. 5 of the drawing. The return-bent end of the element 21 is provided with a metal wearing plate 25 that is secured to its inner surface, a bar 26, of electric-insulating material, being interposed 85 therebetween. A bar 27, of electric insulating material, is located upon the outer surface of the end of the portion 22, and a plurality of rivets 28 serve to clamp the members 22, 25, 26 and 27 rigidly together.

As is illustrated more particularly in Fig. 8, the element 12 is made of relatively thin materials, while the element 21 is made of somewhat thicker materials.

As it is intended that the two elements 12 and 21 shall be traversed by the same main current, suitable means are provided for connecting electrical conductors thereto. A conductor 29 is electrically connected to the fixed end of the outer strip of the element 12, substantially as illustrated in Fig. 3 of the drawing, as by a suitable bolt or screw 31. The opposite end strip of the element 12 is connected to the corresponding strip of the element 21, by a through-bolt 32. The other end or strip of the element 21 is connected,

by any suitable means, to a conductor 33, the connections being such that the same current will traverse the strips or integral portions of the respective elements 12 and 21 in series-circuit relation.

While I have illustrated a definite number of slots in each of the elements 12 and 21, it is to be understood that such number of slots may be employed as may be found desirable or necessary.

A contact terminal 34 is mounted on the element 12, adjacent to the free movable end thereof. The contact terminal 34 is adapted to normally engage a co-operating and substantially stationary contact member 35, that is mounted on a bar 36 of electric-conducting material, which extends through a suitable opening in the bar 15.

Referring more particularly to Fig. 1 of the drawings, I have there illustrated an energy-translating device 37 as comprising a suitable motor. However, such energy-translating device may be a transformer, a generator or a heating coil. A circuit breaker 38 comprises the usual contact terminals and contact bridging members, an actuating coil 39, a core member 41 and a spring 42. Energy for the energy-translating device 37 is provided through a pair of supply-circuit conductors 29 and 43. The elements 12 and 21 are connected in the main circuit substantially as shown in Figs. 1 and 2 of the drawing.

As long as the current traversing the thermal relay 11 and the energy translating device 37 remains below a predetermined value for a predetermined length of time, the positions of the parts of the relay 11 will be substantially that illustrated in Figs. 1 and 8 of the drawing. The auxiliary circuit of the relay 11, controlled by the co-operating contacts 34 and 35, will energize the holding coil 39 of the breaker 38 and the breaker will remain in its closed position.

If, however, an overload is carried by the energy-translating device 37, for a longer time than is permissible, the same current, or a current having a value in accordance with this main current traverses the elements 12 and 21 and causes heating thereof.

As the element 12 has a lower heat-storage capacity than the element 21, by reason of its being thinner, it will heat up sooner and tend to move outwardly or away from the other thermally-responsive element 21. By reason of the hereinbefore described construction of the element 21, which constitutes a latch for the free end of the element 12, the latter element is prevented from moving until the free end of the element 21 is moved longitudinally of the element 12 sufficiently to unlatch the free end of the element 12 by disengagement of the wearing plates 25 and 19.

When such disengagement occurs, the free

end of the element 12 will move suddenly or with a snap action, and disengagement of the co-operating contacts 34 and 35, which control the auxiliary circuit, will also be effected quickly and with a snap action. The final positions of the various parts of the relay 11 and of the circuit are illustrated in Fig. 2 of the drawing, in which the breaker 38 is shown as being in its open position, causing an interruption of the circuit through the energy-translating device 37, to permit the same to cool.

The respective elements 12 and 21 of the relay 11 will begin to cool as soon as the flow of current therethrough has been interrupted, and the element 12 will tend to cool faster than the element 21 by reason of its lower heat-storage capacity. It will, therefore, move back to its normal position sooner than will the free or return-bent end of the element 21. Therefore, when the element 21 has cooled sufficiently to cause it to return to its original position, the return bent end will again extend around the free end of the element 12 and latch the same in its normal operative position, with the two contacts 34 and 35 in operative engagement.

If the circuit breaker 38 be automatic, the circuit will be again closed through the energy-translating device 37, upon reenergization of the coil 39, and operation of the energy-translating device 37 will again be resumed.

The device embodying my invention thus provides a thermal relay having relatively few parts and being, therefore, simple and easy to manufacture. The device further provides a thermal relay that operates with a snap action and that automatically resets itself after a predetermined period of de-energization.

Various modifications and changes may be made without departing from the spirit and scope of the invention, I desire, therefore, that only such limitations shall be placed thereon as are imposed by the prior art.

I claim as my invention:

1. A thermal relay comprising a supporting member, a thermally-responsive element having one end supported thereby, a second thermally-responsive element supported by said member, substantially co-extensive with said first element and having an end portion return-bent around the outer end of said first element to serve as a latch therefor at all temperatures below a predetermined value.

2. A thermal relay comprising a supporting member of electric-insulating material, a longitudinally-slotted, current-conducting, thermally-responsive element having one end mounted on said supporting member, a second longitudinally-slotted, current-conducting thermally-responsive element supported by said member and having its outer end re-

turn-bent around the free end of said first element, whereby it serves as a latch for the same at all currents below a predetermined value.

3. A thermal relay comprising a supporting member of electric-insulating material, a longitudinally-slotted, current-conducting, thermally-responsive element having one end mounted on said supporting member, a second longitudinally-slotted, current-conducting, thermally-responsive element sup-

ported by said member, having a greater heat storage capacity than said first element and having its outer end return-bent around the free end of said first element whereby 15 disengagement of the two elements is effected with a snap action at a predetermined current value.

In testimony whereof, I have hereunto subscribed my name this 7th day of October, 20 1924.

CHARLES H. HODGKINS.
